LEGGING

Lawrence Cleofe, Bayside, N. Y.

Application April 27, 1932, Serial No. 607,859
Renewed December 19, 1933

9 Claims. (Cl. 36—2)

The present invention relates to a legging which is particularly intended for use by infantrymen and cavalrymen and has for one of its important objects to provide, in a manner as hereinafter set forth, a legging embodying novel means through the medium of which the same may be expeditiously put on or taken off.

Another important object of the invention is to provide a legging of the aforementioned character having on its lower end extension flaps which are adapted to be turned in when it is desired not to use the same, in which position said flaps will be invisible.

Other objects of the invention are to provide leggings of the character described which will be simple in construction, strong, durable, reliable in use, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in elevation, looking at the outer side of a legging constructed in accordance with the present invention.

Figure 2 is a view in side elevation showing the legging as it appears in use, viewed from the inner side of the leg.

Figure 3 is a view showing the legging as it appears in use, as it appears on the outer side of the leg.

Referring now to the drawing in detail, it will be seen that the embodiment of the legging constituting the present invention which has been illustrated comprises a body of suitable material which is designated generally by the reference numeral 1, said body including the sections 2 which are stitched together, as at 3. The reference numeral 4 designates a suitable binding at the top of the legging.

The sides of the legging are adapted to be detachably secured together by the separable fasteners 5 through the medium of a slidable operator 6. The fasteners 5 extend from the lower end of the body 1 to a point in spaced relation to the upper end thereof. Above the fasteners 5, a buckle 7 is secured on one side of the body 1 for connection with a strap 8 on the other side of said body 1. On the lower end portion of the body 1, a flap 9 is provided on one side portion, said flap having a snap fastener element 10 mounted thereon for engagement with a companion fas-

tener element 11 on the other side portion of the body 1. When the legging is in use, the flap 9 provides a cover and protector for the sliding operator 6. It may be well to here state that the split in the legging is on the outer side of the leg 60 of the wearer.

Foldable on the lower end of the body 1 are the flaps 12 which are adapted to be folded upwardly between the body 1 and the shoe or which may extend downwardly over the shoe when the legging is in use. The flaps shown are three in number. A strap 13 is connected to the intermediate flap for connection with a buckle 14 which is mounted on an adjacent flap. The element 13 provides an instep strap, as indicated in broken lines in Figure 2 of the drawing. Coacting snap fastener members 15 are provided on the strap 13 and on an adjacent portion of the body 1 for securing the intermediate flap 12 in folded position, in which position the strap 13 extends upwardly 75 between the body 1 and the leg of the wearer.

It is believed that the many advantages of a legging constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. A legging comprising a body for covering the leg and the ankle, and flaps depending from the lower end of the body for covering the instep and the sides of the foot, said flaps being inwardly and upwardly foldable so as to be concealed by the body.

2. A legging comprising a flexible body for covering the leg and the ankle, flaps on the lower end of the body, for covering the instep and sides of the foot, a buckle secured on one of the flaps, and an instep strap secured on another of the flaps for engagement under the instep and connection with the buckle, said flaps being foldable inwardly and upwardly within the body so as to be concealed when not in use.

3. A legging comprising a leg and ankle covering member, flaps depending from the member for covering the instep and side portions of the foot, said flaps being adapted to be folded against the inside of the member so as to be concealed when not in use.

4. A legging comprising a leg and ankle cover-

ing member, flaps depending from the member for covering the instep and side portions of the foot, said flaps being adapted to be folded against the inside of the member so as to be concealed 5 when not in use, a strap depending from one of the flaps and engageable with another one of the flaps and passing under the instep portion of the foot, and means within the member for securing the strap against the side of the member when 10 the flaps are in folded position within the member.

5. A legging comprising a sheet of flexible material for covering the leg and ankle of a wearer, separable fastener elements on the free vertical 15 edges of the sheet, a slide fastener engaged with the fastener elements for securing the sheet in position on the leg and ankle of the wearer, a strap and buckle constricting means cooperating between the upper ends of the said free edges 20 and spaced sufficiently above the upper ends of the fastener elements for constricting the upper end of the legging on the leg of the wearer without causing "bunching" of the material of the sheet near the upper end of the 25 fastener elements, and flaps depending from the sheet for covering the sides and instep portion of the foot of the wearer and adapted to be folded within the legging so as to be concealed when so disposed and not in use.

30 6. A legging comprising a sheet of flexible material for covering the leg and ankle of a wearer, separable fastener elements on the free vertical edges of the sheet, a slide fastener engaged with the fastener elements for securing the sheet in 35 position on the leg and ankle of the wearer, a strap and buckle constricting means cooperating between the upper ends of the said free edges and spaced sufficiently above the upper ends of the fastener elements for constricting the 40 upper end of the legging on the leg of the wearer without causing "bunching" of the material of the sheet near the upper end of the fastener elements, and flaps depending from the sheet for covering the sides and instep portion of the foot 45 of the wearer and adapted to be folded within the legging so as to be concealed when so disposed and not in use, and a shank engaging cross strap on one of the flaps for connection under

the shank portion of the foot with a buckle on another of the flaps when the flaps are in use.

7. A legging comprising a sheet of flexible material for covering the leg and ankle of the wearer, fastener members on the free vertical edges of the sheet for securing the edges together around the leg and ankle of the wearer on one side of the leg and ankle, a single flap on the sheet for engaging the side of the foot and of the instep on the side of the leg opposite the position of the said free edges, smaller flaps for engaging the opposite side of the foot and of the instep, each of said flaps being foldable within the legging so as to be concealed when not in use. 80

8. A legging comprising a sheet of flexible material for covering the leg and ankle of the wearer, fastener members on the free vertical edges of the sheet for securing the edges together around the leg and ankle of the wearer on one side of the leg and ankle, a single flap on the 90 sheet for engaging the side of the foot and of the instep on the side of the leg opposite the position of the said free edges, smaller flaps for engaging the opposite side of the foot and of the instep, each of said flaps being foldable within the legging so as to be concealed when not in use, 95 a shank engaging strap on the single flap, a buckle on one of the smaller flaps to be engaged by the strap.

9. A legging comprising a sheet of flexible material for covering the leg and ankle of the wearer, fastener members on the free vertical edges of the sheet for securing the edges together around the leg and ankle of the wearer on one side of the leg and ankle, a single flap on the 105 sheet for engaging the side of the foot and of the instep on the side of the leg opposite the position of the said free edges, smaller flaps for engaging the opposite side of the foot and of the instep, each of said flaps being foldable within the legging so as to be concealed when not in use, 110 a shank engaging strap on the single flap, a buckle on one of the smaller flaps to be engaged by the strap, and means for securing the shank engaging strap against the inside of the 115 legging when the single flap is folded into concealed position. 120
